OPERATOR FOR WINDOWS

Filed Dec. 31, 1928

ATTORNEYS

UNITED STATES PATENT OFFICE

CLYDE W. KELLY, OF DETROIT, MICHIGAN, ASSIGNOR TO DETROIT STEEL PRODUCTS COMPANY, OF DETROIT, MICHIGAN, A CORPORATION OF MICHIGAN

OPERATOR FOR WINDOWS

Application filed December 31, 1928. Serial No. 329,535.

The invention relates to operators for windows and refers more particularly to operators for screened windows with the screen and operator on the same side. One of the objects of the invention is to provide for the passage of the operator through the screen and to provide means carried by the screen for closing the opening in the screen. Another object is to so arrange the frame bar of the screen through which the operator passes and the closure member for the opening in the screen bar that the assembly presents a neat and pleasing appearance. With these as well as other objects in view, the invention resides in the novel features of construction as more fully hereinafter set forth.

In the drawings:

Figure 1 is an interior side elevation of a screened window embodying my invention;

Figures 2 and 3 are cross sections on the lines 2-2 and 3-3, respectively, of Figure 1;

Figure 4 is an interior side elevation of a portion of the screen with the operator removed;

Figure 5 is an enlarged view of a portion of Figure 1.

As shown in the present instance, the invention is applied to a casement window having the frame 1 and the ventilator 2 for closing the opening in the frame, this ventilator being pivotally mounted upon the side bar of the frame and arranged to swing outwardly. 3 is a screen for the opening in the frame having a hollow frame to which the mesh is secured. The bars of this frame are preferably formed in the same manner as the bottom bar 4 of sheet metal bent to form the lower rectangular chamber 5 and the upper inwardly opening channel 6 into which lat-

ter the edges of the mesh extend, a bar clip 7 being forced into this channel into firm engagement with the edge of the mesh to clamp the same to the bar. This screen is suitably secured against the inner side of the frame 1 as by means of clips upon the frame 1 engaging the upper and lower bars of the screen frame.

For swinging the ventilator 2, I have provided a hand operated mechanism including the operator rod 8, which slidably engages

the guide 9, which in turn is pivotally mounted at its lower end upon the bracket 10 fixedly secured to the inner side of the bottom bar of the frame 1. 11 is a bracket fixedly secured to the inner side of the bottom bar of the ventilator 2. The operator rod 8 has the bent end 12 which is pivotally connected at 13 to the inner end of the bracket 11, this bent end having its lower side cut away to receive the inner end of the bracket so that the lower face of the bracket lies substantially flush with the lower face of the main portion of the operating rod. The bottom bar 4 of the screen 3 is formed with the opening 14 providing for the passage of the bracket 11 and operator rod 8, the bracket engaging in the opening when the ventilator 2 is in closed position in the frame 1. The opening 14 is elongated longitudinally of the bottom bar to provide for swinging of the operator rod when moving the ventilator.

To close the opening 14 there is the sheet metal closure member 15 located within the lower chamber 5 of the bottom bar of the screen, this closure member being preferably formed of sheet metal and bent to channel shape with its base resting upon the base of the lower chamber and its side flanges engaging the sides of the lower chamber. This closure member is formed with the opening 16 therethrough to provide for the passage of the operator rod and the bracket between this rod and the ventilator and since the closure member is slidable longitudinally in the lower bar of the screen and is of sufficient length to at all times extend beyond the ends of the opening 14 in the lower bar this closure member closes the opening 14 and provides for neat appearance.

What I claim as my invention is:

1. An operator for the swinging ventilator of a window having a screen at its inner side provided with a hollow frame bar, comprising an angularly movable arm pivotally connected to the ventilator and extending through an opening in the hollow frame bar, said opening being elongated and substantially larger than the cross sectional area of the arm so as to permit angular movement of the arm, and a channel-shaped closure member

for said opening slidably positioned within said bar and having its side flanges engaging opposite sides thereof, said closure member being movable by said arm to automatically close the opening in all positions of the arm.

- 5 2. An operator for the swinging ventilator of a window having a screen at its inner side provided with a hollow frame bar, comprising a combined sliding and swinging arm 10 pivotally connected to the ventilator and extending through an opening in the hollow frame bar, said opening being elongated and substantially larger than the cross sectional area of the arm so as to permit both sliding and swinging movement of the arm, and a channel-shaped closure member for said opening slidably positioned within the hollow frame bar and having its side flanges engaging opposite sides thereof, said closure 15 member having an opening intermediate its ends of a size substantially equal to the cross sectional area of the arm and through which the arm extends whereby said closure member is moved by said arm and adapted to automatically close the opening in the hollow frame bar in all positions of said operator arm.

In testimony whereof I affix my signature.
CLYDE W. KELLY.
